Primary Examiner — Chun Hoi Cheung*Assistant Examiner* — Brijesh V. Patel(74) *Attorney, Agent, or Firm* — Sand, Sebott & Wernow Co., LPA(57) **ABSTRACT**

A puzzle case that allows for a puzzle to be displayed including a top panel and a base panel that when connected together define a cavity that can hold a puzzle. Typically, each panel comes in four sections that are adapted to be connected and then attached to each other to define a space or cavity to hold a jigsaw puzzle. Mounting points allow for the assembled case to be hung up.

FIG.2

FIG.3

FIG.4

FIG.5

1 PUZZLE CASE

TECHNICAL FIELD

The present invention relates to a puzzle case with an integrated mounting function.

BACKGROUND ART

Jigsaw puzzles are a form of entertainment or mental challenge. Some jigsaw puzzles are highly complex and completing the jigsaw provides the user a sense of achievement. Once the puzzle is completed it is either stored back in the container it came in or can be placed into a bespoke jigsaw puzzle container. There are no jigsaw puzzle containers with the ability to store the final product in a case that can be mounted and displayed or within which the puzzle can be built. Commonly this would be undertaken by using a picture frame.

The object of this invention is to provide a puzzle case to address the above shortcomings or at least to provide a useful alternative.

SUMMARY OF THE INVENTION

In an aspect of the invention there is provided a puzzle case comprising a top panel defined by several top sections adapted to be removably connected together; a base panel defined by several bottom sections adapted to be removably connected together; the top panel adapted to engage the base panel and define a cavity therebetween allowing a jigsaw puzzle to be placed therein.

In preference the top panel is transparent.

In preference the base panel includes of structural reinforcements such as ribs.

In preference the top panel and the base panel are adapted to be removably attached to each other using clips.

In preference each panel comprises of comprising four sections.

It should be noted that any one of the aspects mentioned above may include any of the features of any of the other aspects mentioned above and may include any of the features of any of the embodiments described below as appropriate.

BRIEF DESCRIPTION OF THE DRAWINGS

Preferred features, embodiments and variations of the invention may be discerned from the following Detailed Description which provides sufficient information for those skilled in the art to perform the invention. The Detailed Description is not to be regarded as limiting the scope of the preceding Summary of the Invention in any way. The Detailed Description will refer to several drawings as follows.

FIG. 1 illustrates a completed puzzle case fully assembled including a top panel and a base panel;

FIG. 2 is a bottom perspective view of the puzzle case;

FIG. 3 is an exploded view of the puzzle case;

FIG. 4 is an underside view of the base panel; and

FIG. 5 is an upper and underside view of the panels.

DETAILED DESCRIPTION

The following detailed description of the invention refers to the accompanying drawings. Wherever possible, the same reference numbers will be used throughout the drawings and

2

the following description to refer to the same and like parts. Dimensions of certain parts shown in the drawings may have been modified and/or exaggerated for the purposes of clarity or illustration.

5 Referring to FIGS. 1-3, a puzzle case 10 comprises eight sub-sections. It is however not limited to having eight sub-sections.

The puzzle case 10 with optional mounting accessories comprises of top sections 2, 4, 6, and 8 and at least one clip

10 700 extending downwardly at an edge of each top section. A base panel 20 comprises bottom sections 12, 14, 16, and 18, and at least one clip hole or aperture 702 located on the edge of each bottom section where the corresponding clip on the top panel can engage the corresponding clip hole. A 15 mounting point 301 on the back of the base panel that can be used for hanging the puzzle container for display.

The bottom sections 12, 14, 16, 18 are connected into a single base panel 20. The bottom sections 12, 14, 16, 18 are connected to each other by interlocking male clips 800 that 20 engage females clips 802 by pushing them together as shown in FIG. 2.

The male 800 and female 802 clips are located on the inner edge of each of the bottom sections 12, 14, 16, 18. The inner edge of the bottom section has at least one male 800 25 and one female 802 clip that are collocated to each other on the opposing panel. FIG. 4 displays one arrangement of the clips 800, 802 on the inner edge. It is to be understood that there may be many solutions to how the bottom sections are connected and it is not intended to limit the present invention 30 to this particular embodiment.

The outer edges of the bottom sections comprise female clip holes 702 that are collocate to the top panel's outer edge male clips 700.

The bottom sections 12, 14, 16, 18 include an upper 35 surface that is flat and smooth for the puzzle to rest on. The underside of the bottom sections 12, 14, 16, 18 have a surface with a ribbed extrusion in a grid pattern that adds strength to the panel preventing it from flexing (FIGS. 2, 4). In the centre of each of the bottom sections, a mounting 40 point 301 is located. The mounting point 301 is square in shape and located on the rear of the base panel (FIG. 4), in the centre of the square is a D shape hook. The D shape hook is surrounded by ribbed extrusions that help strengthen the plate as shown in FIG. 5. It is not intended to limit the 45 invention to having mounting points.

After the bottom sections 12, 14, 16, 18 are connected to form a single base panel 20, the jigsaw puzzle can be placed on top of the base panel 20. Of course, the jigsaw puzzle may be constructed within the base panel 20.

50 The top panel 22 is assembled by interlocking each of the top sections 2, 4, 6, and 8 together. Each top section 2, 4, 6, 8 comprises an inner lip 200. The inner lip 200 is the full length of one inner panel edge and is designed to accept an opposing panel's lip 202 by either going over or under the 55 opposing lip 200, 202. Thus alternating sections will have alternate configuration of the opposing lips.

The top sections 2, 4, 6, 8 are connected by pushing together the inner lips 200, 202. The inner lips 200, 202 hold the top sections together to form one top panel 22. Other 60 ways of connecting the sections together would be able to be designed by the relevant person skilled in the art.

Once the top sections are connected into one piece, the top panel 22 can engage the base panel 20. A very thin cavity exists between the top and bottom panels when connected 65 which allows a puzzle to effectively be clamped between the two when finished. The space may only be a few mm in depth, depending on the thickness of the jigsaw puzzle

pieces. The outer edges of the top sections **2, 4, 6, 8** comprise male locking clips **700** that fix into the collocated bottom section's female clip holes **702** on the base panel **20**.

Once the top panel **22** and the bottom panel **20** are connected and form the completed puzzle panel **10**, the puzzle case **10** can be stored or hung up for display using the mounting points **301**.

The bottom sections **12, 14, 16, 18** and top sections **2, 4, 6, 8** are made of suitable plastic material with the top sections being transparent to allow for the viewing of the jigsaw material.

On the back of the bottom sections **12, 14, 16, 18** there are various methods that can be used to hang the base panel on a structure for display. Firstly, there may be plug holes **301** located on the back of each of the bottom sections **12, 14, 16, 18**. The mounting points **301** have a D shaped hook that extends downwardly, the D shape providing a fastener point to mount the base panel onto a structure such as a wall or post. The hook can also be used to attach a string, wire, or rope to allowing the base panel to be hung on a nail. Secondly, the base panel can be stuck to a structure with double-sided adhesive tape by applying it to the flat sections of the base panel.

The puzzle case can be dismantled by unclipping the panel clips **700**, the clips **700** being disengaged by forcing them out of the base panel's clip holes **702**.

When all the clips have been disengaged, they will allow the top panel **22** and the base panel **20** to be separated.

It is to be understood that the number of sections may vary as well as their geometry. But typically, there will be four top sections and four bottom sections that will provide an effective space to hold a completed jigsaw puzzle. Again, we reiterate that the engagement of each section as well as the engagement of the top and base panels may be accomplished by various means and the above description is not intended to limit the invention to this embodiment.

The reader will now appreciate the present invention which provides a puzzle protection case. A further advantage is that the size of the panels allows them to be packed into a box that includes the puzzle pieces. Thus the user can purchase a jigsaw puzzle that includes sections that can be assembled together to provide support for the puzzle.

LIST OF COMPONENTS

The drawings include the following integers.
2, 4, 6, 8 top sections
10 puzzle case
12, 14, 16, 18 bottom sections
20 base panel
22 top panel
200 inner lip
202 opposing lip
301 mounting point
700 male locking clips
702 female clip holes
800 interlocking male clip
802 female clip

Further advantages and improvements may very well be made to the present invention without deviating from its scope. Although the invention has been shown and described in what is conceived to be the most practical and preferred

embodiment, it is recognized that departures may be made therefrom within the scope of the invention, which is not to be limited to the details disclosed herein but is to be accorded the full scope of the claims to embrace any and all equivalent devices and apparatus. Any discussion of the prior art throughout the specification should in no way be considered as an admission that such prior art is widely known or forms part of the common general knowledge in this field.

In the present specification and claims (if any), the word "comprising" and its derivatives including "comprises" and "comprise" include each of the stated integers but does not exclude the inclusion of one or more further integers.

The invention claimed is:

1. A puzzle case comprising:
a top panel which is transparent, wherein the top panel comprises a plurality of top sections configured to be removably connected to one another;
a bottom panel comprising a plurality of bottom sections configured to be removably connected to one another; outer edge walls provided on the bottom panel and extending upwardly beyond an upper surface of the bottom panel,
wherein an area of the upper surface of the bottom panel is adapted to receive jigsaw puzzle pieces thereon; wherein the top panel is operatively engageable with the bottom panel around an outer perimeter of the bottom panel;
- 25 a cavity defined by the top panel and the bottom panel when operatively engaged with one another; wherein the outer edge walls encircle the cavity when the puzzle case is assembled;
- 30 a plurality of clips, wherein the top panel and the bottom panel are removably attached to one another using the plurality of clips; and
- 35 wherein the cavity of the puzzle case has a depth which is sufficient to receive an assembled jigsaw puzzle within the cavity and which enables the assembled jigsaw puzzle to be clamped between the top panel and the bottom panel and to be displayed through the top panel.

2. The puzzle case as in claim 1, wherein the bottom panel includes structural reinforcements.

3. The puzzle case as in claim 1, wherein the bottom panel includes ribs.

4. The puzzle case as in claim 1, wherein the top panel comprises four top sections and the bottom panel comprises four bottom sections.

5. The puzzle case as in claim 1, wherein the outer edge walls are of a height adapted to correspond to a thickness of the jigsaw puzzle receivable therein.

6. The puzzle case as in claim 1, wherein the plurality of bottom sections is opaque.

7. The puzzle case as in claim 1, further comprising at least one mounting point provided on a rear surface of the bottom panel, wherein the at least one mounting point is adapted to enable securement of the puzzle case to a vertical surface.

8. The puzzle case as in claim 1, wherein the cavity is of a depth small enough to clamp a finished jigsaw puzzle between the top panel and the bottom panel.
